UNITED STATES PATENT OFFICE.

FREDERICK COLLIER TYGARD, OF PITTSBURGH, PENNSYLVANIA.

INTERNAL-COMBUSTION ENGINE.

1,107,382.

Specification of Letters Patent. Patented Aug. 18, 1914.

Application filed August 2, 1910, Serial No. 575,169. Renewed December 20, 1913. Serial No. 808,046.

To all whom it may concern:

Be it known that I, FREDERICK C. TYGARD, a citizen of the United States of America, and resident of Pittsburgh, in the county of 5 Allegheny and State of Pennsylvania, have invented certain new and useful Improvements in Internal-Combustion Engines, of which the following is a specification.

This invention relates to certain new and 10 useful improvements in internal combustion engines of the reciprocating type, and it has for its objects to provide an improved internal combustion engine having as its basic feature or principle, the division of a combustible charge, with suitable means for the introduction of the charge into a cylinder, compressing said charge to the desired pressure, and transferring a portion of the same to an adjoining chamber, and igniting, expanding and exhausting the remaining portion in said cylinder, and then retransferring the first portion of said charge to the same or adjoining cylinder or cylinders, where it is ignited, expanded and exhausted. 15 20 25 30 35 40 45

I have found that the above cycle of operations works preferably in three cylinder type of engine, the first and third cylinders using the ordinary four stroke cycle, and the intermediate cylinder expanding and exhausting the charges transferred alternately from the first and third cylinders. By this cycle of operation, the charges are reduced to atmospheric pressure, rendering the exhaust noiseless and thereby utilizing the largest proportion of the energy of fuel not lost in radiation. By my novel construction the three cylinders have the same number of impulses per revolution as four cylinders of the four cycle type; that is, I obtain four impulses from three cylinders at each two revolutions of the crank shaft and thereby gain practically the advantages of one cylinder over the usual four cylinder type engine. I am enabled to employ small firing chambers which tends to reduce the heat and am enabled to expand to nearly double the volume, this depending upon the relative size of the intermediate cylinder.

I employ a single valve common to all of 50 the cylinders and constructed and connected up to run at substantially one-half the speed of the crank shaft whereby the cycle is effected and puppet valves and their co-operating cams, lifters and springs are entirely eliminated. My construction also permits 55 of the building of air cooled cylinders of

larger diameter than the former types and permits of compactness and simplicity of the arrangement of the parts, as well as the employment of simple means for changing the 60 time of opening and closing of the ports while the engine is in operation.

Other objects and advantages of the invention will hereinafter appear and the novel features thereof will be particularly 65 pointed out in the appended claims.

The invention is capable of embodiment in a variety of forms, that herein illustrated being what I at the present time consider the most preferable.

The invention, in its preferred form, is clearly illustrated in the accompanying drawings, which, with the numerals of reference marked thereon, form a part of this specification, and in which—

Figure 1 is a substantially central longitudinal section through the engine with parts in elevation illustrating my improvement. Fig. 2 is a section on the line 2—2 of Fig. 1, looking in the direction of the arrows. Fig. 3 is a section on the line 3—3 of Fig. 1, looking in the direction of the arrows. Fig. 4 is an enlarged elevation of the rotary valve removed. Fig. 5 is a cross section on the line 5—5 of Fig. 4, looking in the direction of the arrows. Fig. 6 is a cross section on the line 6—6 of Fig. 4, looking in the direction of the arrows. Fig. 7 is a cross section on the line 7—7 of Fig. 4, looking in the direction of the arrows. Fig. 8 is a cross section on the line 8—8 of Fig. 4, looking in the direction of the arrows. Fig. 9 is a cross section on the line 9—9 of Fig. 4, looking in the direction of the arrows. Fig. 10 is a diagrammatic view of the valve seen in Fig. 4, as flattened out. Fig. 11 is a view similar to Fig. 1 showing the application of the principle to a single cylinder engine. Fig. 12 is a diagrammatic view of the valve employed in connection with the single cylinder engine.

Like numerals of reference indicate like parts throughout the several views.

Referring to the drawings, 1, 2 and 3 designate the cylinders in which are mounted 105 to reciprocate the pistons 4, 5 and 6, these latter being of any of the well-known forms of construction.

7 is the crank shaft and 8 the fly wheel thereon. 10, 11 and 12 are the piston rods connecting the pistons 4, 5 and 6 with the cranks 13, 14 and 15 respectively. No claim

is made to any particular form of crank connection, in fact, these elements, as well as others of the machine not specifically defined, may be all of any of the well-known 5 or approved forms of construction.

16 is the crank case, in this instance shown as in sections united in any well-known manner, as seen at 17, and having the lugs or extensions 18 for attachment to the chassis.

10 The cylinder casting may be secured to the crank case in any suitable manner, as for instance shown at 19, providing detachability of the parts when desired. The cylinder casting is provided with a suitable jacket, as 15 seen at 20, for reception of a cooling medium, such as water, as seen at 21, said jacket extending around the top of the engine forming a jacket 22 for the reception of the cooling medium, as 23, so as to keep the 20 valve cool.

24 is a hollow rotary valve mounted within a suitable tubular valve casing 25 mounted upon the upper ends of the cylinders, as seen clearly in Figs. 1 and 2.

25 26 is the inlet for the charge of mixed air and gas, but as the elements pertaining to this, form no part of the present invention, they have not been illustrated, it being deemed sufficient to show only the end of the 30 pipe through which the supply is delivered.

This valve is designed to be actuated from the crank shaft and to be run at substantially one-half the speed of the latter. For this purpose I mount upon the crank shaft 7 25 a sprocket wheel 27, as seen clearly in Fig. 3, around which passes a chain 28 which, in turn, passes around the sprocket wheel 29 of substantially twice the diameter of the sprocket wheel 27, this chain and sprocket 40 wheel being of any of the well-known types, preferably of that class known as the silent or noiseless type. The sprocket wheel 29 is mounted upon a stub shaft 30 suitably journaled in axial alinement with the valve 24, 45 a suitable clutch 31 being provided, as indicated in Fig. 1. These sprockets and the chain are inclosed within a suitable casing 32, as shown in Figs. 1 and 3, for an obvious purpose. 34 is a spring arranged within an 50 extension 35 of said casing, as seen clearly in Fig. 1, and tending to keep the clutch members normally in engagement. This spring may sometimes be omitted, as seen in Fig. 11. The shaft of the upper sprocket is 55 mounted in ball or roller bearings, as seen at 36, so as to lessen the friction and to prevent the chain from pulling down on the valve, allowing the said chain to merely drive the valve by reason of the clutch hereinbefore referred to. Suitable oil cups, as seen at 37, 60 in Fig. 1, may be provided for keeping the valve well lubricated.

The valve 24 is provided intermediate its ends with a partition 38, in this instance substantially midway of the intermediate cylinder.

der 2. The valve 24 is further provided with the intake openings 39 and 40, which are disposed near opposite ends and upon diametrically opposite sides of the valve, as will be readily understood upon reference to Figs. 70 4 and 10.

The valve 24 is provided near one end with the transfer opening 41 and the exhaust opening 42, while at the opposite end and upon the opposite side of the valve there is 75 provided the transfer opening 43 and the exhaust opening 44. Intermediate the exhausts 42 and 44 are the intake openings 45 and 46 adjacent to which is the exhaust openings 47 and 47^a. The relative disposition of these various intake openings and exhausts will be readily understood upon reference to Figs. 1, 4 and 10.

48 is the manifold intake chamber and 49 the manifold exhaust chamber. From the former there extends the pipes 50 and 51, seen in Figs. 1 and 2, which communicate with the exterior of the valve 24 upon opposite sides of its partition 38. 52, 53 and 54 are pipes which afford communication between the manifold exhaust chamber 49 and the exterior of the valve, the relative location of these parts being best understood upon reference to Fig. 1.

It may sometimes be desirable to give the 95 valve more lead or earlier opening or less lead and later opening of the ports, and while this may be done in a variety of ways, I have chosen to illustrate herein one means for accomplishing this purpose which I have 100 found simple yet efficient. It will be best understood upon reference to Figs. 1 and 3, particularly the latter, wherein 55 is a horizontal shaft suitably journaled in the casing 32 and rigid with this shaft so as to be actuated thereby are the arms 56 and 57 carrying at their outer or free ends respectively the rollers 58 and 59. Fast to the shaft 55 is an arm 60 having an operating handle 61, by means of which the shaft may be turned. 105 It will thus be seen that by simply turning this arm so as to revolve the shaft in one direction or the other, tension may be put upon either one or the other side of the chain as circumstances may require to change the lead and time of opening of the ports. It is to be understood, however, that the mechanism for bringing about a division of the charge is in no wise restricted to this 110 tension mechanism and no claim is made in this application to the latter, which will form the subject-matter of a subsequent application, but which is herein illustrated merely as an example of one form of efficient 115 means for accomplishing this purpose.

63 and 62 are intake and outlet ports respectively at the upper end of the cylinder 1.

64 and 65 are inlet and outlet ports respectively at the upper end of the cylinder 3. 130

66 is an enlarged port at the upper end of the cylinder 2 which serves for both the inlet and the outlet, first to the one cylinder and then to the other, it being noted that the 5 ports 45 and 46 are so disposed that when the one is open to the cylinder 2, the other which is diametrically disposed in the valve is closed, and vice versa.

With the parts constructed and arranged 10 substantially as hereinbefore described and as herein illustrated, the operation is as follows: With the parts in the position in which they are seen in Fig. 1, cylinder 1 has just completed the explosion stroke, and is 15 to exhaust on its upward travel, cylinder 2 has received the portion of charge formerly compressed and transferred from cylinder 1 and is in position to ignite the same, expanding the transferred charge on piston 5, downward stroke. Piston 6, in cylinder 3, has received a combustible charge and is in 20 position to begin the compressing and transfer of one portion thereof to the chamber in the valve. The combustible charge is introduced 25 into the one cylinder, and is then compressed to the desired pressure and a predetermined portion, say one-half, more or less, is transferred to the adjoining cylinder, where it is ignited, expanded and the products of combustion expelled or exhausted, the other half or remaining portion of said 30 charge having been ignited, expanded and the products of combustion expelled or exhausted in the first cylinder. The rotation 35 of the valve is to timed as to bring about these results to the best advantage.

It is to be understood that the cylinders are each provided with a sparking plug of usual form, as seen at 67, and also that suitable water connections for the cooling jacket 40 will be provided, as seen for instance in Fig. 1.

I may sometimes embody substantially the same principle and construction in the one 45 cylinder engine, and such embodiment is illustrated in Fig. 11 wherein the various parts which are similar to those in the construction shown in Fig. 1 are designated by similar reference characters with the addition of the prime marks, for instance the cylinder is designated 1', the piston 4', the crank shaft 7' etc. The valve is connected up and timed so as to run at substantially one-third of the crank shaft speed. The 50 valve is illustrated diagrammatically in Fig. 12, 39' being the cylinder intake, 42' the intake of the valve, 41' the outlet from the valve and 69 and 70 the exhausts.

68 seen in Fig. 11 designates the port in 60 the end of the cylinder for communication at proper times with the transfer port 42' and the retransfer port 41', the valve being shown in Fig. 11 in such position as to bring these ports 41' and 38 into register.

65 From the foregoing description, it will be

seen that I have devised a simple and efficient novel form of internal combustion engine in which in the forms shown in Figs. 1 to 10 inclusive I obtain four impulses at each two revolutions of the crank shaft, 70 while in the single cylinder type I obtain two impulses from each three revolutions of the crank shaft, there being two impulses in two revolutions of the crank shaft and one complete revolution performing suction 75 and compression or no work effect.

While the structural embodiment of the device as hereinbefore disclosed is what I at the present time consider preferable, it is evident that the same is subject to 80 changes, variations, and modifications in detail, proportion of parts etc., and I, therefore, do not intend to restrict myself to the details of construction hereinbefore set forth, but reserve the right to make such 85 changes, variations and modifications as come properly within the scope of the protection prayed.

What is claimed as new is:—

1. In an internal combustion engine of 90 the reciprocatory type, the combination with a cylinder, of means of compressing therein an excessive explosive charge and rotary means for dividing said charge into predetermined parts, one for immediate use 95 in said cylinder and the other separately segregated, for a successive operation.

2. In an internal combustion engine of the reciprocatory type, the combination with a cylinder, of means of compressing 100 therein an excessive explosive charge and rotary means for dividing said charge into predetermined parts, one part for immediate use and the other separately segregated for a separate successive operation in the same 105 cylinder.

3. In an internal combustion engine of the reciprocatory type, the combination with a cylinder, of means of compressing 110 therein an excessive explosive charge and rotary means for dividing said charge into predetermined parts, one part for immediate use and the other separately segregated for a successive operation in a cylinder.

4. In an internal combustion engine of 115 the reciprocatory type, the combination with a cylinder, of means of compressing therein an excessive explosive charge and means for dividing said charge into predetermined parts, one part for immediate use 120 and the other separately segregated for a successive operation in a cylinder, and means for the transfer and retransfer of said segregated portion back to a cylinder.

5. In an internal combustion engine of 125 the reciprocatory type, the combination with a cylinder of means of compressing therein an excessive explosive charge, means for dividing said charge into predetermined parts, one part for immediate use 130

and the other separately segregated, for a successive operation in a cylinder, means for the transfer and retransfer of said segregated portion back to a cylinder for its 5 ignition, and suitable means to ignite, expand and exhaust said portion.

6. In an internal combustion engine of the reciprocating type, a cylinder adapted to receive an excessive explosive charge, a 10 piston arranged to compress said charge, means adapted to divide said charge into predetermined parts, means for separately segregating one of said parts for an immediate succeeding charge in a cylinder, means 15 for the transfer and retransfer of said segregated part and suitable means for separately igniting the same.

7. In an internal combustion engine of the reciprocating type, a cylinder adapted 20 to receive an explosive mixture, a piston in said cylinder arranged to compress said mixture, means to transfer a portion of said mixture to another chamber, means for igniting, expanding and exhausting the re- 25 maining portion, with means to re-transfer the previously transferred unignited portion of the said mixture to a cylinder, and means to ignite, expand, expel or exhaust said portion.

30 8. In an internal combustion engine of the reciprocating type, a cylinder adapted to receive an explosive mixture, a piston in said cylinder arranged to compress said mixture, means for the division and trans- 35 fer of a portion of said mixture to an adjoining chamber, means for igniting, expanding, and expelling or exhausting the remaining portion of said mixture, together with means for the re-transfer of the pre- 40 viously compressed, divided and transferred unignited portion of said mixture to a cylinder, and means for igniting, expanding, expelling or exhausting the re-transferred portion of said mixture.

45 9. In an internal combustion engine of the reciprocating type, a chamber adapted to receive therein an explosive charge, a piston arranged to compress said charge, a valve, together with suitable means to trans- 50 fer a portion of said compressed charge to an adjoining chamber, with means to re-transfer said portion to a chamber, means to ignite, expand, and expel the said portion of said charge, and suitable means to 55 ignite, expand, and expel or exhaust the un-transferred portion thereof.

60 10. In an internal combustion engine of the reciprocating type, a cylinder adapted to receive an explosive charge, a piston therein arranged to compress said charge, and means embodying a rotary valve adapted to receive and transfer to an adjoining chamber a portion of said charge.

65 11. In an internal combustion engine of the reciprocating type, a cylinder adapted to

receive an explosive charge, a piston therein arranged to compress said charge, and rotary means for dividing such charge into predetermined parts, one for immediate use and the remainder for a separate operation 70 in a cylinder, and re-transfer means for a divided portion of said charge to a cylinder.

12. In an internal combustion engine of the reciprocating type, a cylinder, with means embodying a rotary valve for transferring a portion of the charge from said cylinder to another cylinder, means for varying the lead of said valve. 75

13. In an internal combustion engine of the reciprocating type, a cylinder, with 80 means embodying a rotary valve for transferring a portion of the charge from said cylinder to another cylinder, means for varying the lead of said valve, and connections between said valve and the crank shaft. 85

14. In an internal combustion engine of the reciprocating type, a cylinder, with means embodying a rotary valve for transferring a portion of the charge from said cylinder to another cylinder, means for 90 varying the lead of said valve, and connections between said valve and the crank shaft and constructed to actuate said valve at less than the crank shaft speed. 95

15. In an internal combustion engine of the reciprocating type, a cylinder, with means embodying a rotary valve for transferring a portion of the charge from said cylinder to another cylinder, means for varying the lead of said valve, connections 100 between said valve and the crank shaft and constructed to actuate said valve at less than the crank shaft speed, and means for varying the lead of said valve.

16. In an internal combustion engine of the reciprocating type, a cylinder adapted to receive an excessive explosive charge, and a single valve provided with means to divide, receive, separately segregate and return a portion of said charge to a cylinder. 105

17. In an internal combustion engine of the reciprocating type, rotary means for dividing an explosive charge into predetermined parts, one for immediate use in the cylinder in which it is compressed and the other separately segregated for successive 115 operation.

18. In an internal combustion engine of the reciprocating type, a cylinder, means for compressing therein an excessive explosive charge, rotary means for dividing said charge into predetermined parts and separately segregating the same for a successive operation. 120

19. In an internal combustion engine of the reciprocating type, a cylinder, means for compressing therein an excessive explosive charge, and rotary means for separately segregating a portion of such charge for a successive operation. 125

20. In an internal combustion engine of the reciprocating type, a chamber adapted to receive an explosive charge, a piston arranged to compress said charge, means embodying a rotary valve adapted to receive and transfer to another chamber a portion of said compressed charge, and means to re-transfer substantially all of said portion to the aforesaid chamber to be ignited and expanded and the products of combustion expelled.

21. In an internal combustion engine of the reciprocatory type, a cylinder, means for the introduction and compression of an explosive mixture therein, and means embodying a chambered valve for the division and transfer and re-transfer of a portion of the charge compressed in said cylinder.

22. In an internal combustion engine of the reciprocatory type, the combination with a cylinder, of means for compressing therein an excessive explosive charge, and means for dividing such charge into predetermined parts, one for immediate use in said cylinder and the other separately segregated, for a successive independent operation in a cylinder, and re-transfer means for a divided portion of said charge to a cylinder.

23. In an internal combustion engine of the reciprocatory type, the combination with a cylinder, of means of compressing therein an excessive explosive charge and means for dividing said charge into predetermined parts, one part for immediate use and the other separately segregated for a separate

successive independent operation in a cylinder.

24. In an internal combustion engine of the reciprocatory type, means for dividing an explosive charge into predetermined parts, one for immediate use in the cylinder in which it is compressed and the other separately segregated for successive independent operation in a cylinder, and re-transfer means for a divided portion of said charge to a cylinder.

25. In an internal combustion engine of the reciprocatory type, a cylinder, means for compressing therein an excessive explosive charge, means for dividing said charge into predetermined parts and separately segregating the same for a successive independent operation in the cylinder, and re-transfer means for a divided portion of said charge to a cylinder.

26. In an internal combustion engine of the reciprocatory type, a cylinder, means for compressing therein an excessive explosive charge, means for separately segregating a portion of such charge for successive independent operation in a cylinder, and re-transfer means for a divided portion of said charge to a cylinder.

Signed by me at Pittsburgh, Pa., this 30th day of July 1910.

FREDERICK COLLIER TYGARD.
